WALTER D. CHAPPELLE, OF WYOMING, ONTARIO, CANADA.

BOTTLE ATTACHMENT

No. 836,018.

Specification of Letters Patent.

Patented Nov. 13, 1906.

Application filed April 14, 1906. Serial No. 311,809.

To all whom it may concern:

Be it known that I, WALTER D'ESMOND CHAPPELLE, a subject of the King of Great Britain, residing at the village of Wyoming, 5 in the Province of Ontario and Dominion of Canada, have invented new and useful Improvements in Bottle Attachments, of which the following is a specification.

The invention relates to an improved indicating attachment for bottles, primarily designed for use with bottles containing poison or the like and serving to indicate to the dispenser the nature of the contents of the bottle.

15 The main object of the present invention is the production of an indicating device of the class described which is adapted for ready and convenient use with any bottle and which when in operative position will 20 prevent the withdrawal of the cork of the bottle until the device is moved to inoperative position, thereby serving to indicate to the dispenser the nature of the contents of the bottle and preventing the accidental 25 or unintentional use of improper materials in filling prescriptions or the like.

The preferred details of structure of the present invention will be described in the following specification, reference being had 30 particularly to the accompanying drawings, in which—

Figure 1 is a sectional view, partly in elevation, illustrating the application of my improved indicator. Fig. 2 is a plan of the 35 same with the bottle removed. Fig. 3 is an elevation of the device. Fig. 4 is a plan of a slightly-modified form of guard. Fig. 5 is a vertical section of the same.

Referring particularly to the drawings, my 40 improved indicating attachment comprises an annular band 1 of a diameter and height to wholly include the projecting portion of the cork 2 beyond the mouth of the bottle 3. The upper edge of the band is vertically 45 slitted and cut away to provide a series of spur-shaped projections 4, the alternate projections being bent at right angles to the plane of the band, thereby providing a series of spurs extending vertically from the 50 upper edge of the band and a second series of spurs extending horizontally from the upper edge of the band. The spurs thus provided serve to indicate the presence of the guard in the attempt of the dispenser to remove 55 the cork from the bottle, thereby advising him of the nature of the bottle's contents.

Depending from the band 1 is an elongated strip 5, preferably extending the full height of the band and projecting below the same, being formed at the lower end to provide an 60 eye 6, arranged to loosely receive a spring holding-clip 7, which preferably at the point opposite its engagement with the eye is open to provide for its engagement with the bottle-neck. Diametrically opposite the hinge- 65 strip 5 I arrange a locking-strip 8, also secured to the outer surface of the band 1 and depending below the lower edge of the band. At the lower end the locking-strip 8 is laterally offset or bent to provide a recess 9, de- 70 signed when the indicator or guard is in place to engage the rim 10 at the mouth of the bottle and secure the guard against accidental displacement. The locking-strip projects below the bent portion 9 to provide a 75 handle portion 11, by which the locking-plate may be disengaged from the rim 10.

In use the band 1 completely envelops the projected portion of the cork and is secured in applied position by means of the locking-strip 8, thereby preventing its accidental displacement and insuring that the dispenser be advised of the nature of the contents of the bottle when making the initial effort to withdraw the cork. Should he de- 85 sire to use the material in the bottle, however, the guard may be removed from its position relative to the cork by disengaging the locking-strip 8 from the rim 10 and swinging the guard as a whole on the hinge connection 90 at 6 from about the cork, the guard in the inoperative position being disposed as illustrated in dotted outline in Fig. 1.

The guard as a whole is initially applied to the desired bottle by causing the spring 7 to 95 embrace the neck of the bottle in an obvious manner, by which construction the guard is adapted for use with bottles having necks of varying diameters within the limit of the clip, though, if preferred, said clip may be 100 more or less flexible and adapted to be manually forced into engaging position with the bottle-neck.

In the event the cork proper of the bottle is provided with the ordinary flattened wing 105 projections the band 1 may be manually bent into such shape as to provide for its embracing the stopper, it being understood that the band is sufficiently flexible to permit such operation.

Referring particularly to Figs. 4 and 5, wherein is shown a slightly-modified form of

guard, it will be noted that the elongated strip for movably supporting the spring-holding clip 7 and a locking-strip are in this form of device formed integral of a single 5 length of material. One end of the material is bent into an eye 12 to receive the spring-clip and projecting therefrom to form a strip 13, corresponding to the strip 5 in the preferred form. The wire at the upper end of 10 the strip is passed through the band of the guard and curved in contact therewith and on the inner side to a point about diametrically opposite its entrance when it is projected through the band and bent downward to form 15 a locking-strip 14, conforming to the locking-strip 8 in the preferred form. The return length conforms to the initial projection for the locking-strip and is passed through the band at a point spaced from the 20 exit-point and curved oppositely to the first-mentioned portion in contact with the interior surface of the band, being at an approximately diametrical opposite point passed through the band in alignment with 25 the entrance of the projection of the clip-holding strip and extended downward, conforming in outline to said strip, being previously intertwined therewith at 15 beyond the surface of the band to provide for se-

curing the integral-formed member in fixed 30 relation to the band.

Having thus described the invention, what is claimed as new is—

1. A poison-guard for bottles comprising a 35 clip to engage the bottle-neck, a band arranged to encircle the cork and of greater height than the projecting portion thereof, said band having a hinge connection with the clip.

2. A poison-guard for bottles comprising a 40 clip to engage the bottle-neck, a band arranged to encircle the cork and of greater height than the projecting portion thereof, said band having a hinge connection with the clip; and means for securing the band in 45 operative relation with the cork.

3. A poison-guard for bottles comprising a bottle-engaging clip, a band having hinge connection with the clip, the upper end of the band being formed with vertically-arranged spur-points, and a locking-strip depending from the band. 50

In testimony whereof I affix my signature in presence of two witnesses:

WALTER D. CHAFFELLE.
